INVENTOR:

I. V. Newsom
BY *Muns & Co.*
ATTORNEYS.

UNITED STATES PATENT OFFICE.

ISAAC V. NEWSOM, OF MOUNT MEIGS, ALABAMA.

PLOW.

SPECIFICATION forming part of Letters Patent No. 249,079, dated November 1, 1881.

Application filed July 7, 1881. (Model.)

To all whom it may concern:

Be it known that I, ISAAC V. NEWSOM, of Mount Meigs, county of Montgomery, and State of Alabama, have invented certain useful Improvements in Plows, of which the following is a specification.

Figure 1 is a side elevation of my improvement, shown as applied to a plow-beam. Fig. 2 is a front elevation of the same, the plow-beam being shown in section. Fig. 3 is a sectional plan view taken through the line *x x*, Fig. 2. Fig. 4 is a sectional elevation taken through the line *y y*, Fig. 2. Fig. 5 is a plan view of the catch-block.

15 The object of this invention is to facilitate the adjustment of plows and promote convenience in repairing them.

A represents the plow-beam.

19 *B* is the plow-standard, which is made in two parts, or is slotted longitudinally, to receive the beam *A* in its upper part and the plow-fastening bolt in its lower part. The standard *B* is hinged by a bolt, *C*, at or near its middle, to a metal block, *D*, bolted to the lower side of the beam *A*, so that said standard can be adjusted to regulate the pitch of the plow.

25 In the upper end of the standard *B* is formed a slot, *E*, to receive a bolt, *F*, which passes through one or another of the notches or cross-grooves formed to receive it in the metal block *G*, bolted to the top of the beam *A*.

The bolt *F* is secured in place, when in one of the notches *H* in the catch-block *G*, by 30 tightening the nut of the bolt. With this construction, by loosening the nut of the bolt *F* and raising the said bolt out of its notch *H*, the pitch of the standard *B* can be regulated as desired.

40 *I* is the mold-board, which has a recess, *Q*, along the landside edge to receive the detachable piece or colter *J*. The lower part of the colter *J* is secured to the mold-board *I* by a bolt or rivet, *K*, and its upper part is secured in place by the bolt *L*, that secures the mold-board *I* to the standard *B*. 45

45 In the lower forward part of the mold-board *I* is formed a dovetailed recess, *M*, to receive the dovetailed tongue *N*, formed upon the upper edge of the point or share *O*. The point 50 or share *O* can be secured in place by a bolt, *P*, passing through its tongue *N* and through the mold-board *I*; or the bolt *P* may be omitted and the point or share held to its place by friction. With this construction the colter *J* 55 and the share *O*, when worn, can be readily detached and replaced by new ones.

55 The mold-board *I* is strengthened against lateral movement by the brace or cross bar *R*, the outer end of which is bolted or otherwise 60 secured to or is formed upon the rear side of the lower part of the mold-board *I*. The outer end of the brace *R* is bolted to the lower end of the standard *B*.

Having thus fully described my invention, I 65 claim as new and desire to secure by Letters Patent—

65 The combination, with a plow-beam carrying a lower block, *D*, and an upper notched block, *G*, of the bifurcated standard *B*, straddling said beam, hinged at *C* to said block *D*, slotted near the top, and held by bolt and nut to any of the notches in block *G*, as and for the purpose specified.

ISAAC V. NEWSOM.
